(57) **CLAIM**

The ornamental design for a display apparatus, substantially as shown and described.

DESCRIPTION

FIG. 1 is a perspective view of a display apparatus.

FIG. 2 is a rear elevation of the display apparatus of FIG. 1.

FIG. 3 is a front elevation of the display apparatus of FIG. 1.

FIG. 4 is a left elevation view of the display apparatus of FIG. 1.

FIG. 5 is a right elevation view of the display apparatus of FIG. 1.

FIG. 6 is a top plan view of the display apparatus of FIG. 1; and,

FIG. 7 is a bottom plan view of the display apparatus of FIG. 1.

The broken lines are included for illustrative purposes only and form no part of the claimed design.

1 Claim, 4 Drawing Sheets

FIG. 1

FIG. 2**FIG. 3**

FIG. 4

FIG. 5

FIG. 6

FIG. 7
